UNITED STATES PATENT OFFICE.

JOSEPH BERGE, OF FLINT, MICHIGAN, ASSIGNOR TO CHAMPION IGNITION COMPANY, OF FLINT, MICHIGAN, A CORPORATION OF MICHIGAN.

DESIGN FOR AN ODOMETER HUB-CAP.

53,981.

Specification for Design.

Patented Nov. 4, 1919.

Application filed April 14, 1919. Serial No. 290,095. Term of patent 14 years.

To all whom it may concern:

Be it known that I, JOSEPH BERGE, a citizen of the United States, residing at Flint, in the county of Genesee and State of Michigan, have invented a new, original, and ornamental Design for Odometer Hub-Caps, of which the following is a specification, reference being had to the accompanying drawing, forming part thereof.

Figure 1 is a front elevation of a hub cap for odometers, showing my new design.

Fig. 2 is a side elevation of the same.

I claim:

The ornamental design for an odometer hub cap, as shown.

In testimony whereof I hereunto affix my signature.

JOSEPH BERGE.
